(57) **CLAIM**

The ornamental design for a railing-mountable plant pot, as shown and described.

DESCRIPTION

FIG. 1 is a top perspective view of a railing-mountable plant pot showing my new design;

FIG. 2 is another top perspective view of the railing-mountable plant pot of FIG. 1, shown mounted on a railing and containing a plant;

FIG. 3 is a side elevation of the plant pot of FIG. 1, with the opposite side not shown but being identical to what is shown in FIG. 3;

FIG. 4 is an end elevation of the plant pot of FIG. 1, with the opposite end not shown but being identical to what is shown in FIG. 4;

FIG. 5 is a top plan view of the railing-mountable plant pot of FIG. 1;

FIG. 6 is a bottom plan view of the railing-mountable plant pot of FIG. 1;

FIG. 7 is a top perspective view of another railing-mountable plant pot showing my new design;

FIG. 8 is a side elevation of the plant pot of FIG. 7, with the opposite side not shown but being identical to what is shown in FIG. 8;

FIG. 9 is an end elevation of the plant pot of FIG. 7, with the opposite end not shown but being identical to what is shown in FIG. 9;

FIG. 10 is a top plan view of the railing-mountable plant pot of FIG. 7; and,

FIG. 11 is a bottom plan view of the railing-mountable plant pot of FIG. 7.

The broken lines are included for the purpose of illustrating environmental structure and portions of the railing mountable plant pot that form no part of the claimed design.
